UNITED STATES PATENT OFFICE

JOHN G. JACKSON, OF DETROIT, MICHIGAN, ASSIGNOR TO SQUARE D COMPANY, OF DETROIT, MICHIGAN, A CORPORATION OF MICHIGAN

REINFORCED BLOCK STRUCTURE FOR ELECTRIC FIXTURES

Application filed September 21, 1931. Serial No. 564,243.

This invention relates generally to porcelain bases and refers more particularly to those designed for supporting electric parts such as fuse clips and the like.

5 In the accompanying drawings:

Figure 1 is a perspective view of a fuse box containing a base embodying my invention;

Figure 2 is a detail perspective view of the base with electrical parts mounted thereon;

10 Figure 3 is an edge elevation of the base;

Figure 4 is a cross sectional view taken on the line 4—4 of Figure 3;

Figure 5 is a detail perspective view of the reenforcement.

15 Few electrical base materials except porcelain are non-carbonizable but porcelain alone is subject to breakage and initial fracture thereof may cause displacement of live electrical parts mounted thereon, consequently 20 such bases are unsatisfactory.

My invention includes means for increasing the strength of the porcelain by the introduction into slots or recesses therein of steel and cement, the construction and arrangement being such that the cement at a relatively low temperature may be placed into the recesses and embodies in its composition qualities which permit it to bond steel to porcelain without entailing fracture of 25 the porcelain due to any difference in expansion or contraction of steel and of porcelain over normal ranges of temperatures of use or of handling. Such reenforcement of porcelain by means of steel rods or bars has 30 not been possible by direct introduction of steel into porcelain when molded therein, as subsequent firing operations at high temperatures cause expansion and contraction of steel and porcelain as well as adverse chemical actions between the two materials.

40 Referring now to the drawings, 1 is a base embodying my invention mounted within a suitable box or container 2 and supporting suitable fuse clips 3 and their electrical conductors 4 and terminals 5. As shown, this base is provided in the top and bottom thereof with suitable recesses 6 and 7 respectively for receiving the electric parts just mentioned and is provided in opposite longitudinal 45 edges 8 and 9 with longitudinally extending 50

channels or recesses 10 and 11 respectively having keying grooves or slots 12 and 13 in certain walls thereof. Suitably deformed or twisted steel bars 16 are placed as far as practical in the recesses 10 and 11 upon opposite sides of the neutral axis of the base and are held in place by cement 17. Preferably this cement comprises a mixture of sulphur and finely ground flint and is placed in the recesses while in a molten condition. 55 Such a cement bonds to steel and to porcelain and at the temperature of application does not cause objectionable strains to be set up in the structure. In fact, the bond between the steel and porcelain is such that the parts 60 are held firmly together without subsequent tendency to fracture under various normal conditions of change in temperature whether sudden or slow, and affords a greater resistance to fracture than when porcelain alone 65 is employed as a base material. However, should the base 1 be fractured as a result of undue pressure or mechanical shock, the electrical parts 3, 4 and 5 respectively thereon will not be appreciably displaced. Thus 70 a safer and more durable structure is provided.

75 While it is believed that from the foregoing description the nature and advantages of the invention will be readily apparent, I 80 desire to have it understood that I do not limit myself to what is herein shown and described and that such changes may be resorted to when desired as fall within the scope of what is claimed.

85 What I claim as my invention is:

1. In combination, a porcelain base having a recess in an edge thereof, cement in the recess, and a steel reenforcement in the cement.

90 2. In combination, a porcelain base provided in one longitudinal edge thereof with a longitudinally extending recess, cement in the recess, and strips of steel embedded in the cement and extending longitudinally of the 95 recess.

3. In combination, a porcelain base having a recess, a steel reenforcement in the recess, and a connection between the steel and porcelain including cement in the recess. 100

4. In combination, a substantially flat porcelain base provided in one edge with a longitudinally extending channel having an anchorage groove in a wall thereof, steel members within and extending longitudinally of the channel, and a connection between said members and porcelain including cement anchored within the channel and enveloping said steel members.
- 10 5. In combination, a substantially flat elongated porcelain base provided in opposite longitudinal edges thereof throughout substantially the length of the base with longitudinally extending laterally opening channels, cement within said channels, and steel reenforcing members embedded within the cement and extending throughout substantially the entire length of the channels, said channels and steel reinforcements having portions upon opposite sides of the neutral axis of the base.
- 15 6. In combination, a base of vitreous material provided in one edge with a longitudinally extending recess, portions of the recess being upon opposite sides of the neutral axis of the base, reenforcing means for the base including steel members in the recess upon opposite sides of the neutral axis of the base, and means in the recess bonding the steel members to the base of vitreous material.
- 20 7. In combination, a porcelain base provided in one edge with a longitudinally extending recess, a steel reenforcement in the recess, and cement within the recess bonding the steel reenforcement to the porcelain base.
- 25 8. In combination, a porcelain base having a recess therein, a steel reenforcement for the base located within said recess, and means within the recess bonding the steel reenforcement to the porcelain base.
- 30 9. In combination, a porcelain base having a recess therein, a steel reenforcement for the base located within said recess, and means for bonding the steel reenforcement to the base including a cement comprising a mixture of sulphur and finely ground flint within the recess and enveloping the steel reenforcement.
- 35 10. In combination, a porcelain base provided with a longitudinally extending channel having an anchorage groove in a wall thereof, a steel member within and extending longitudinally of the channel, and a connection between said member and porcelain including cement enveloping said member within said channel and engaging said anchorage groove.
- 40 11. In combination, a porcelain base having an elongated recess therein, one wall of said recess having a longitudinally extending anchorage groove, a steel member within and extending longitudinally of the recess, and a connection between said member and porcelain including cement within said recess and engaging said anchorage groove.
- 45 12. In combination, a porcelain base having an elongated recess therein, cement in said recess, and a strip of steel embedded in the cement and extending longitudinally of said recess.
- 50 13. In combination, a porcelain base having a recess therein, a steel reenforcement for the base located within said recess, a wall of said recess being provided with an anchorage groove, and means bonding the steel reenforcement to the porcelain base including means within the recess and engaging the anchorage groove.
- 55 In testimony whereof I affix my signature.
